UNITED STATES PATENT OFFICE.

WILLIAM REID, OF NEWARK, NEW JERSEY.

PROPELLER.

1,012,441.

Specification of Letters Patent. Patented Dec. 19, 1911.

Application filed July 22, 1910. Serial No. 573,229.

To all whom it may concern:

Be it known that I, WILLIAM REID, a citizen of the United States, and a resident of Newark, county of Essex, and State of New Jersey, have invented certain new and useful Improvements in Propellers, of which the following is a full, clear, and exact description.

The main object of this invention is to provide a propeller having a plurality of sets of blades, those of one set being directly in front of the blades of the other set, that is to say the blades of the various sets are so arranged that a plane passing longitudinally through the center of the propeller shaft will intersect all of the blades at the centers thereof.

Another object of the invention is to provide a propeller having a plurality of sets of blades having two blades in each set, said blades extending radially from the hub in diametrically opposite directions and the blades of the rear set or sets being directly in the rear of the blades of the forward set.

A further object of the invention is to so space the sets of blades that those of one set will not interfere with the proper working of those of the set next in front, the object being to prevent the rear blades engaging the water from the forward blades.

With these and other objects in view, the invention will be hereinafter more particularly described with reference to the accompanying drawings, which form a part of this specification, and will then be pointed out in the claims at the end of the description.

In the drawings, Figure 1 is a side elevation of the propeller. Fig. 2 is a rear view thereof; and Fig. 3 is a view looking at the ends of the propeller blades.

Referring to the various parts by numerals, 1 designates the propeller shaft; 2 the propeller hub which carries the propeller blades. To this hub are secured two sets of blades A and B, the blades B being the rear blades and the blades A the forward blades. The blades A are arranged radially with respect to the hub and the longitudinal center line thereof is perpendicular with respect to the propeller shaft. These blades may, of course, be given any

desired pitch and may be of any suitable shape. The blades B are placed a suitable distance in the rear of the blades A and the longitudinal center line of each of said blades is oblique to the longitudinal center line of the propeller shaft so that said blades incline rearwardly from the hub. These blades are, of course, arranged at diametrically opposite points as illustrated clearly in Fig. 2 and are directly in the rear of the blades A, as also illustrated clearly in Fig. 2. The purpose of the rearward inclination of these blades B is to prevent said blades receiving the water from the blades A.

The rear blades are arranged oblique to the longitudinal line of the shaft so that the space between the blades is equal to twice the width of the blades from the hub up to their place of greatest width. As the blades, shown in the drawings, gradually increase in width from the hub to a point near their outer ends it is necessary to incline the rear set of blades rearwardly in order to maintain said blades from each other a distance equal to twice the width of the blades. It is manifest that if the blades were of the same width throughout all points in their length they might be arranged parallel. I have found that by so spacing the sets of blades from each other, the desired result is secured and a boat fitted with such a propeller will travel faster than a boat fitted with the ordinary propeller.

It will, of course, be understood that this propeller may be arranged to be rotated toward the left or the right as may be desired; and that the blades may be given any desired pitch and be of any desired shape. It is essential, however, that the distance between the blades at all points throughout the length thereof should be at least twice the width of the blades.

Having thus described my invention, I claim as new and desire to secure by Letters Patent:—

A propeller comprising a hub, and forward and rear sets of blades thereon, the forward set of blades extending radially outward in opposite directions with their axes perpendicular to the hub axis, the rear set of blades being located in alinement with and to the rear of the forward set of blades with their longitudinal axes in a

2
plane passing through the axis of the hub and said blades, said rear blades being inclined rearward relative to the forward blades and spaced from said forward blades in such a manner that the distance between the blades on a line parallel with the axis of the shaft is, at any point between the hub and the widest part of the blades, sub-

stantially equal to twice the width of either blade at that point.

This specification signed and witnessed this eighteenth day of July A. D. 1910.

WILLIAM REID.
